UNITED STATES PATENT OFFICE.

FRANKLIN H. BOWLY, OF NEW YORK, N. Y., ASSIGNOR OF ONE-FOURTH TO FRANCIS L. WELLMAN, ONE-FOURTH TO WILLIAM W. GOOCH, AND ONE-FOURTH TO WARREN G. DEMAREST, OF NEW YORK, N. Y.

APPARATUS FOR PRODUCING ALCOHOL.

No. 866,426.

Specification of Letters Patent.

Patented Sept. 17, 1907.

Application filed March 21, 1907. Serial No. 363,697.

To all whom it may concern:

Be it known that I, FRANKLIN H. BOWLY, a citizen of the United States of America, residing at New York, in the county of New York and State of New York, have 5 invented new and useful Improvements in Apparatus for Producing Alcohol, of which the following is a specification.

This invention relates to apparatus for producing alcohol by synthetic process, already known, and one 10 of the principal objects of the same is to provide an apparatus of comparatively simple construction, by means of which such alcohol may be produced at slight cost.

Another object of the invention is to provide an 15 apparatus which is capable of rapid operation for producing alcohol from acetylene gas, hydrogen and sulfuric acid by properly combining the gas and hydrogen and submitting the same to the absorbing action of the acid to which water (about 33%) is then added and 20 then distilling the compound, and condensing the vapor arising from the still.

These and other objects may be attained by means 25 of the apparatus illustrated in the accompanying drawing, in which the figure is a section and partial elevation of an apparatus made in accordance with my invention.

Referring to the drawing for a more particular description of my invention, the numeral 1 designates 30 an acetylene gas generator of simple form, comprising a casing mounted on suitable legs 2 and provided with a water inlet pipe 3, said pipe being provided with a valve 4 by means of which the flow of water may be regulated for the purpose of generating gas from the calcium carbid placed within the casing through a 35 suitable hopper or spout 5.

A pipe 1^a provided with a valve 2^a communicates with the generator 1, for injecting hydrogen into the generator.

A suitable gage 6 for indicating the pressure of gas 40 may be superposed upon the generator 1.

A tubular shaft 7 communicates with the interior of the generator 1 and is supported upon a leg 8 secured to the floor 9.

Mounted to rotate upon one end of the tubular shaft 45 7 is a drum 10 lined with sheet lead or other suitable acid proof material 11, said drum being provided with a series of shelves 12.

A shaft 13 is secured to the drum at one end, and the opposite end is mounted to rotate in a bracket 14 secured to a partition wall or other suitable support 16, and on the shaft 13 is a pulley 17 designed to receive a belt 18 leading to any suitable source of power for the rotation of the drum 10.

A suitable cock or faucet 19 communicates with the drum near its periphery. 55

A still 20 is mounted upon a suitable furnace 21, and provided with a vertical pipe 22 extending from its top or upper side and extending through the floor 9, said still being lined with acid-proof material of suitable nature and provided with a draw-off pipe 23 provided with a suitable cock or valve 24. 60

A funnel 25 having its upper end extending through the floor 9 is provided with a discharge pipe 26 which communicates with the interior of the still 20 and is provided with a suitable valve 27. 65

A flaring condenser 28 is fitted at its smaller end to the pipe 22 by a liquid tight joint, said condenser being located in a room above the still, and superposed upon the floor 9. Any suitable means may be employed for cooling the condenser 28, the extended area 70 and the flaring construction of the condenser serving to assist in acquiring a low temperature around the pipe 22. A draw-off cock 29 is provided at a point near the lower end of the condenser. 75

The operation of my invention may be briefly described as follows: Calcium carbid is placed in the casing 1 and water is started through the pipe 3 to generate acetylene gas. Hydrogen is then injected into the generator through the pipe 1^a thus converting the nascent acetylene gas into ethylene. Sulfuric acid being placed 80 in the drum 10, the latter is revolved, and the ethylene passes through the hollow shaft 7 into the interior of the drum and is mixed thoroughly with the sulfuric acid until the ethylene is completely absorbed. The sulfuric acid is placed in the drum through the faucet 85 19, said faucet being brought around toward the top of the drum for this purpose. When the indicator has indicated a sufficient absorption of gas, the faucet 19 is turned to the position shown in the drawing, and the cock is opened to permit the product to flow into 90 the funnel 25 and from thence into the still 20 where the product is distilled, (after having had a requisite quantity of water added to it,) and passing up through the pipe 22 in the form of a vapor it is discharged into the condenser 28 and drawn off as pure alcohol by 95 means of the cock or faucet 29. The sulfuric acid is recovered through the cock or faucet 24 to be again used in the drum 10.

From the foregoing it will be understood that the nascent acetylene gas evolves considerable heat and 100 thus readily combines with the hydrogen.

Having thus described the invention, what I claim is:

1. In an apparatus of the character described, a gas generator, a mixing drum, a hollow shaft establishing communication between the generator and drum, a still, a 105 pipe leading from the still, a condenser having a flaring

wall and surrounding said pipe, and means whereby the contents of the mixing drum may be led to the still, substantially as described.

2. In an apparatus of the character described, a gas generator, a mixing drum, a hollow shaft establishing communication between said generator and drum, a still, a condenser surrounding the outlet pipe from the still, a faucet communicating with the drum, a funnel under said faucet leading to the still, means for rotating said drum, and a draw-off pipe leading from the still.
5. In an apparatus of the character described, a generator, a drum provided with interior shelves, a hollow

shaft leading from the generator to the drum, means for rotating said drum, a still, connections between the drum and still, a pipe rising from the still, a flaring condenser surrounding said pipe, and a discharge faucet at the lower portion of said condenser.

In testimony whereof, I affix my signature in presence of two witnesses.

FRANKLIN H. BOWLY.
